CLAIM

The ornamental design for a holder for a writing instrument, as shown and described.

DESCRIPTION

FIG. 1 is a perspective view of a holder for a writing instrument showing my new design;

FIG. 2 is a perspective view of a second embodiment of my design of FIG. 1; and,

FIG. 3 is a perspective view of a third embodiment of my design of FIG. 1.

The writing instruments depicted by means of broken lines in FIGS. 1, 2, and 3 have been shown for illustrative purposes only and form no part of the claimed design.
